Alfred W. Bell,

BY Richard Oliver,

ATTORNEY

UNITED STATES PATENT OFFICE.

ALFRED W. BELL, OF MILAN, TENNESSEE.

ELECTRIC IGNITING DEVICE.

1,312,229.

Specification of Letters Patent.

Patented Aug. 5, 1919.

Application filed November 1, 1916. Serial No. 123,983.

To all whom it may concern:

Be it known that I, ALFRED W. BELL, a citizen of the United States, residing at Milan, in the county of Gibson and State of Tennessee, have invented certain new and useful Improvements in Electrical Igniting Devices, of which the following is a specification.

The present invention has reference, generally, to ignition apparatus; and, the invention relates, more particularly, to improved electrical ignition means.

The invention has for its principal object to provide an electrical ignition means, whereby, explosive fuses and other similar devices may be automatically ignited in an efficient and safe manner, thus, lessening the liability of various forms of accidents, particularly attributable to premature explosions.

As an object of equal importance, the invention also aims to provide a novel safety attachment for the ignition means, which attachment will prevent the accidental closing of the igniting or working circuit when it is desired to have the device inoperative.

Among other aims and objects of the invention may be recited, the provision of a device of the character mentioned, with a view to compactness, and in which the number of parts are few, the construction simple, the cost of production small, and efficiency and operation high.

Other improvements and novel details in the construction and arrangement of the various parts of the device will be brought out more in detail in the description to follow, which, for a clear understanding of the invention, should be considered in connection with the accompanying drawings forming a part hereof, and wherein is disclosed, for the purpose of illustration, a convenient and satisfactory embodiment of the invention.

In the drawings:

Figure 1 is a side elevation of the improved device,

Fig. 2 is a front elevation thereof showing the safety switch arm in disconnected position,

Fig. 3 is a similar view wherein the safety switch arm is shown in connected position, and

Fig. 4 is a fragmental vertical section of the device.

Similar characters of reference are employed in all of the above described views, to indicate corresponding parts.

Referring now in detail to the several figures of the drawing, the tubular casing is generally indicated by the numeral 1, the casing consisting of a metallic tube 2 and an exteriorly arranged insulating covering 3, the covering being of a shape complementary to the tubular member 2. An annular screw threaded sleeve 4 is secured to one end of the member 2, by means of rivets or other similar fastening means 5, it being noted, that the end of the member 2 is extended slightly beyond the insulating covering 3. A second screw threaded sleeve 6 is provided and is turned into engagement with the threads of the sleeve 4, the outer end of the sleeve 6 having an inturned flange 7 formed thereon. A battery 8 is received within the member 2 and has one terminal thereof engaged by a screw threaded cap 9, which is received over the rear or remaining end of the casing 1.

With more especial reference to the present improvements, a circular base 10, formed of insulating material is engaged with the outer marginal edge of the screw threaded sleeve 4 and is held thereon by means of the sleeve 6, the flange 7 of which engages the outer face of the circular base 10. Binding terminals 11 are arranged upon the base 10 and have turned into engagement therewith, thumb nuts 12, the terminals 11, as will be obvious, being rigidly secured to the base 10 by locking nuts 13.

The sparking coil 14 is supported about a suitable core 15, the said sparking coil being secured to the inner face of the base 10 by means of the screw 16 which is passed therethrough and embedded within a portion of the core 15. A contact cap 17 is arranged over the free end of the sparking coil and is suitably connected therewith, the cap being adapted to normally engage the remaining terminal or pole of the battery 8, thus, affording means whereby the current may be introduced into the sparking coil 14. The remaining end of the sparking coil is engaged with one of the binding terminals 11, thus, completing one side of the electrical circuit.

A pivotal switch arm 18 is arranged upon the remaining binding terminal 11 and is adapted to rotate freely thereabout. It is

evident that when the switch arm is swung outwardly, it will engage the flange 7 of the sleeve 6. This sleeve is connected to the tubular member 2, upon which the remaining 5 pole of the battery 8 is grounded. As the sparking coil is connected to the terminals 11, a circuit will be formed over the sparking coil 14, over the terminals 11 in a connection with the same feed wires of the system, the switch 18 and sleeve 6 together with the casing. However, when the switch arm is swung inwardly from the flange 7, or as shown in Fig. 2, the circuit will be broken.

The operation of the device may be re-15 viewed as follows:

The lead wires of the ignition system are connected to the binding terminals or posts 11, whereupon the safety switch 18 is swung to a point whereat it will engage a portion 20 of the sleeve 6. To render the device inoperative, the safety switch 18 is moved to a neutral position.

The foregoing description and the drawings have reference to what may be considered the preferred, or approved form of 25 my invention. It is to be understood that I may make such changes in construction and arrangement and combination of parts, material, dimensions, et cetera, as may prove 30 expedient and fall within the scope of the appended claims.

Copies of this patent may be obtained for five cents each, by addressing the "Commissioner of Patents, Washington, D. C."

I claim:

1. An ignition device, including, in combination with a portable casing carrying a source of electrical energy, which is connected thereto, an insulating base removably secured to said casing, binding terminals on said base, a sparking coil carried by the base and connected with one of said circuit terminals and said source of electrical energy, and a pivotal switch arm arranged upon the remaining terminal adapted for engagement with the casing whereby the passage of current through said terminals may be controlled.

2. An igniting device including a portable casing carrying a source of electrical energy, which is connected thereto, binding terminals carried upon and insulated from said casing, a sparking coil connected with one of 50 said circuit terminals and said source of electrical energy, and a pivoted switch arm arranged upon the remaining terminal adapted for engagement when said casing, whereby the passage of current through said terminals may be controlled.

In testimony whereof I affix my signature in presence of two witnesses.

ALFRED W. BELL.
